DESIGN FOR A CLOTHESPIN

Thomas T. Taylor and Edward A. Chandler,
Hawthorne, Calif.

Application December 29, 1945, Serial No. 125,137

Term of patent 14 years

(Cl. D17—6)

To all whom it may concern:

Be it known that we, Thomas T. Taylor, a subject of King George VI of Great Britain, and Edward A. Chandler, a citizen of the United States, residing in the city of Hawthorne, county of Los Angeles, and State of California, have invented a new, original, and ornamental Design for a Clothespin, of which the following is a specification, reference being had to the accompanying drawing, forming part thereof.

Fig. 1 is an edge elevational view of a clothespin, showing our new design.

Fig. 2 is a side elevational view.

Fig. 3 is an end elevational view, looking upward from the bottom in Fig. 1.

The essential features of our design for a clothespin reside in the parts shown in full lines.

We claim:

The ornamental design for a clothespin, substantially as shown and described.

THOMAS T. TAYLOR.
EDWARD A. CHANDLER.
